Application May 21, 1943, Serial No. 487,876

2 Claims. (Cl. 15—151)

This invention relates to a mop head.

It is usual in the construction of a mop head to utilize jaws for clamping a mop element formed of metal with some sort of toggle-action or spring-clamping means for holding the jaws in assembled position.

One of the objects of this invention is to eliminate the necessity of using any metal parts.

Another object of this invention is to provide a mop head formed of wood which when wet will so swell as to more firmly bind the parts in assembled relation.

Another object of this invention is to provide a simple construction which may be inexpensively provided and quickly assembled.

Another object of this invention is to provide a construction which can be made wholly of wood and strings or some flexible element suitably manipulated about clamping jaws.

With these and other objects in view, the invention consists of certain novel features of construction, as will be more fully described and particularly pointed out in the appended claims.

In the accompanying drawing:

Fig. 1 is a perspective view of the mop head assembled and with the handle broken off;

Fig. 2 is a view similar to Fig. 1 illustrating the two clamping jaws with the mop element removed and with the strands incompletely fastened in position;

Fig. 3 is a perspective view of the center portion of the mop element;

Fig. 4 is a central longitudinally sectional view of the arrangement shown in Fig. 1 and showing more particularly the manner of arranging the binding strands.

In proceeding with this invention we provide two wooden clamping jaws and slot the same at their ends. The slots are usually centrally located so as to register one with the other. Two flexible strands knotted at their ends are then used to fasten the jaws in assembled relation to bind the mop element in position. These strands are led through the slots of the jaws at one end and then across and through the slots of the jaws at the other end for suitable fastening. The knots in the ends of the strands prevent them from drawing through the slots.

With reference more particularly to the drawing 10 designates one jaw and 11 the other jaw of the mop head. The jaw 10 is centrally slotted as at 12 and 13 at its opposite ends while the jaw 11 is similarly slotted as at 14 and 15 at its opposite ends. The under surface of the jaw 10 is concave as shown at 16 while the upper surface of 55

the jaw 11 is convex as designated at 17. The arcs of these two surfaces are along radii of substantially the same dimension.

The jaw 10 has a threaded opening as at 32 and a handle 33 threaded as at 34 is screwed into this opening.

The mop element designated generally 18 consists of a plurality of rope-like strands 19 having a band 20 extending about their central portions to bind them in assembled relation. This band also serves to designate a convenient location for binding the mop element between the jaws.

The mop element 18 is laid with its band 20 located between the jaws 10 and 11 and these jaws are brought up firmly on the opposite sides of this mop element and against the band 20. A binding strand 21 having a knot 22 is positioned with its knot 22 drawn up snugly against the underside of the slot 14 of the jaw 11 and extended upwardly through the slot 14 and then swung into the slot 12 of the jaw 10. At the opposite side the strand 23 having a knot 24 is positioned with its knot 24 against the under side of the slot 15 and extends up through the slot 15. This strand 23 is then swung into the slot 13 and extends upwardly therethrough similarly to that shown in Fig. 2. The sizes of the strands 21 and 23 are such that they will fit tightly in the equal width slots and the walls of the slots will bind 30 against the strands which will be held under compression. The strands are each then further fastened as follows; for instance strand 21 is extended across the length of the jaw 10 on one side of handle 33 and beneath the strand 23 as shown at 25 and is then moved into the slot 13 as at 26 (see Fig. 4) and then into slot 15 and around the portion 27 of the jaw 11 and thence again down through the slot 15 as shown at 28. Similarly the strand 23 is led across the jaw 10 on the other side of handle 33 down through the slots 12 and 14 as at 29 and then around the portion 30 of the jaw 11 and again down through the slot 14 as at 31. This arrangement provides a very firm locking of the two jaws together and 45 in case that swelling occurs of these wooden jaws these strands will be bound more firmly in position. Likewise the strands themselves may swell and serve to cause binding of the jaws in a firm and fixed relation even though they do not swell or decrease their slot opening.

We claim:

1. A mop head comprising a pair of rigid jaw members each having a slot at each end portion thereof and with the slots of one jaw member aligned with the slots of the other jaw member,

a mop element between said jaw members and means to bind the members in firm engagement with the mop element, said means consisting of at least two flexible strands each knotted at one end portion to prevent it from being drawn through a slot and each of said two strands extending from the knotted portion through the slots of the members at one of their ends and then along the jaws towards each other through the slots at the opposite ends of the members and each wound about a portion of the last jaw engaged by said strands and doubly wound through the slot of the said last engaged jaw said knotted portions being positioned in said slots at opposite ends of said jaw members.

2. A mop head comprising a pair of rigid jaw members each having a slot at each end portion thereof and with the slots of one jaw member

aligned with the slots of the other jaw member, a mop element between said jaw members and means to bind the members in firm engagement with the mop element, said means consisting of at least two flexible strands each knotted at one end portion to prevent it from being drawn through a slot and each of said two strands extending from the knotted portion through the slots of the members at one of their ends and then along the jaws towards each other through the slots at the opposite ends of the members, said slots and strands being so relatively sized that each strand will engage the side walls of the slot in which it is positioned with sufficient friction to be bound in the slot.
